INVENTOR.

UNITED STATES PATENT OFFICE

2,206,499

CONCEALED HINGE

Charles Dumelin, Detroit, Mich.

Application March 9, 1939, Serial No. 261,688

2 Claims. (Cl. 16—164)

My invention relates to a concealed hinge adaptable for automobile doors, and the object is to provide a simply constructed hinge for the purpose specified.

5 A further object is to provide a hinge that may be easily secured to a body and door, the hinge consisting of two plate members comprising overlapping end flanges, means including two sets of ball bearings inserted between said overlapping flanges, one set of said bearings forming the control and the other set of bearings forming the floating hinge axis. The control is provided with a transverse groove, and the floating hinge axis is provided with a circular groove, the two sets of bearings engage each other and pivot the door about the control.

10 With this and other objects in view the invention consists in a hinge of the class and for the purpose specified, which is simple in construction and operation, efficient in use and which is constructed as hereinafter described and claimed.

15 The invention is fully disclosed in the following specification, of which the accompanying drawing forms a part in which the separate views of my invention are designated by suitable reference characters in each of the views and in which:

20 Fig. 1 is a sectional plan view of the hinge, the dotted lines illustrate part of sheet metal surrounding a body and door.

25 Fig. 2 is a sectional plan view of the hinge showing it in an open position.

30 Fig. 3 is a plan view of the stationary plate member.

35 Fig. 4 is an elevation of the two half plates of the stationary member.

Fig. 5 is an elevation of the inner plate.

40 Fig. 6 is a plan view and Fig. 7 an elevation view of the pivotal plate member.

45 Fig. 8 is an elevation of the two plate members and the two sets of bearings in position.

In said drawing 1 denotes part of sheet metal around a body pillar and 2 is part of sheet metal around the edge of a door, 3 indicates the outer door flange construction.

50 The hinge is shown with two plate members forming overlapping end flanges, and two sets of ball bearings inserted therein. One set of bearings forms the control by a transverse groove,

and the other set of bearings forms the floating hinge axis provided by a circular groove.

The hinge as shown consists of two half plate members 5 and 6 and inner plate 7, plate member 8, control bearings A and pivotal bearings B.

5 Plate members 5 and 6 are each provided with a circular groove 11 extending about an edge of each flange of the members, the flanges also having ball receiving recesses 12.

Plate member 8 is provided with transverse 10 grooves 13 and ball receiving recesses 14.

15 The parts are assembled as indicated in Figs. 1—2 and 8. The inner plate 7 is secured to plate 5 and 6 after the ball elements are positioned in their ball receiving recesses 12 and 14.

20 It will be understood, however, that my invention is not necessarily limited to any specific use herein shown and disclosed.

Having fully described my invention what I claim and desire to receive by Letters Patent is:

25 1. A door hinge of the concealed type comprising two members provided with end flanges, the end flanges of one member being parallel and overlapping the end flanges of the other member, pivotal means extending between each pair of adjacent overlapping flanges, said pivotal means comprising a ball element seated in a recess in a flange and movable in an arc-shaped groove in an adjacent flange and pivotal control means extending between said adjacent flanges, 30 said control means comprising a ball element seated in a recess in a flange and movable in a groove in an adjacent flange, said grooves extending in the closed position of the members outwardly and forwardly of the door jamb.

35 2. A door hinge of the concealed type comprising two members provided with end flanges, the flanges of one member being parallel and overlapping the flanges of the other member, pivotal means extending between each pair of 40 adjacent overlapping flanges, said pivotal means comprising ball elements seated in recesses in the flanges, and movable in grooves in adjacent flanges, one of said grooves being arc-shaped and extending about an edge of one flange and the 45 other groove extending obliquely in an adjacent flange, said grooves extending in the closed position of the members outwardly and forwardly of the door jamb.

CHARLES DUMELIN. 50
